US00D941984S

(12) **United States Design Patent** (10) Patent No.: **US D941,984 S**
(45) Date of Patent: ** Jan. 25, 2022

(54) **COMBINATION CEILING FAN MOTOR
HOUSING AND LIGHT FIXTURE**

(71) Applicant: **HUNTER FAN COMPANY**,
Memphis, TN (US)

(72) Inventor: **Alexander Jonathan Haggar**,
Memphis, TN (US)

(73) Assignee: **Hunter Fan Company**, Memphis, TN
(US)

(**) Term: **15 Years**

(21) Appl. No.: **29/781,963**

(22) Filed: **May 3, 2021**

Related U.S. Application Data

(63) Continuation of application No. 29/713,245, filed on Nov. 14, 2019, now Pat. No. Des. 921,881, which is a continuation of application No. 29/593,483, filed on Feb. 9, 2017, now Pat. No. Des. 875,914.

CLAIM

The ornamental design for a combination ceiling fan motor housing and light fixture, as shown and described.

DESCRIPTION

FIG. 1 is a top perspective view of a combination ceiling fan motor housing and light fixture, showing my new design; FIG. 2 is a bottom perspective view thereof;

FIG. 3 is a top view thereof;

FIG. 4 is a bottom view thereof; and,

FIG. 5 is a side view thereof.

Portions of the combination ceiling fan motor housing and light fixture shown in broken line and ceiling fan environmental subject matter shown in broken line form no part of the claimed design.

1 Claim, 5 Drawing Sheets
